UNITED STATES PATENT OFFICE.

ROY W. SCHWEIKER, OF LANSDALE, PENNSYLVANIA.

LIGHTING FIXTURE.

Application filed December 29, 1925. Serial No. 78,123.

This invention relates to lighting fixtures of that general class which are more particularly adapted for use in connection with a mirror in a bath room or lavatory, or, 5 near a sink in a kitchen, or for use on a ceiling, or, on the outside of a building.

One of the objects of the invention is to provide novel means for clamping the lamp socket to the canopy in a manner permitting 10 easy assembly of the parts and their securement in position when installing the fixture on the wall or ceiling and which will enable the fixture to be readily taken apart for purpose of inspection and repair.

15 Another object is to provide a novel shade or globe mounting or unit which can be used as such at any point and in connection with any wiring, moulding, or fixture, wherein tension screws or fastening means are 20 done away with, and the shade or globe may be quickly and easily applied, or removed, and will be securely held when in position. My improved shade or globe mounting is not restricted to use in connection 25 with the canopy hereinafter described, nor with any other canopy as it may be used wherever such a device is applicable.

A still further object is to provide in a combination of parts, improved means for 30 attaching a lamp socket to the canopy and for holding a shade or globe thereon, particularly one of the improved form I have devised.

Another object of the invention is to provide 35 a lighting fixture which will be provided with means for the attachment of a plug for use of current in connection with any appliance or device, such as an electric fan, curling iron heater, water heater or 40 similar accessory. To that end the arrangement is such that a plug may be inserted and the current used independently of the use of the lamp and without possibility of a short circuit or shock to the person attaching the appliance.

45 My improvements, while not restricted to use in connection with a fixture having a shell or canopy of any particular material, are peculiarly adapted for use in connection 50 with porcelain fixtures adapted for use in bath rooms, lavatories, kitchens, and in out-door locations. While not restricted to any particular design of fixture, I have shown the present improvements in connection 55 with a design for mirror lighting

fixtures, application for which was filed December 16, 1925, Serial No. 15,770.

The invention is susceptible of modification and I do not limit the improvements to the precise construction hereinafter fully described and claimed and which is shown in the accompanying drawings.

One embodiment of the invention is illustrated in the accompanying drawings, in which:

Figure 1 is a front elevation;

Figure 2 is a rear elevation;

Figure 3 is a vertical section, one form of shade and lamp being shown in dot and dash lines to illustrate how the shade or globe is held;

Figure 4, is a detail view of the lamp socket, inner ring, and gasket;

Figure 5 is a detail perspective of my novel globe or shade holding ring unit, the shade appearing in dot and dash lines; and

Figure 6 is a detail view of the inner ring.

The canopy 1 which is illustrated in connection with my present improvement is 80 shown as of the design for which I have made the aforesaid application, but other designs may be used without departing from the present invention. The canopy 1 as shown, may be of porcelain, being provided 85 with an internal flange 2 having notches 3. The lamp socket has a base 4, a body 5, and a ring 6.

The metallic screw shell 7 is secured to the base 4, while the ring 6 screws on said 90 shell.

Interposed between the body 5 and the ring 6 is a metallic ring or annulus 8 which has a lug 9 entering a notch 10 in the body 5 to prevent the ring from twisting. The 95 ring or annulus 8 is of a size adapting it to rest against the inner face of the flange 2 and it constitutes one of the clamping rings to hold the lamp socket in position in the canopy 1.

A rubber gasket 11 is interposed between the ring 6 and the annulus 8 to form a cushion, enabling the ring 6 to be screwed up tightly without danger of damage and to assist in holding the ring 8 in position 100 so that it will not turn or become loosened.

A combined shade or globe holder and clamping ring 12 is adapted to be clamped against the outer face of the flange 2 by screws 13 which pass through the notches 110

3 and are screwed into the threaded openings 14 in the ring 8. The screws 13 clamp the rings 8 and 12 on opposite sides of the flange 2 and thereby firmly hold the lamp socket in position.

The combined shade holder and ring 12 preferably snugly fits the recess 14 in the face of the canopy 1, for the purpose of more firmly anchoring said ring 12.

It is obvious that by removing the screws 13, the rings 8 and 12 will be disconnected, the lamp socket loosened, and then upon manipulating the parts, any necessary repairs or change in wiring may be readily made.

The shade or globe holding ring is provided with integral springy fingers 15 which are bowed to receive the neck of the shade or globe. To hold the shade or globe at its neck so that it will not become accidentally detached and also to keep it from sagging or rattling I provide a coil spring 16 which extends from one of the fingers to another. This spring is pressed back or stretched when the shade or globe is snapped into position and then, in connection with the fingers, it retains the shade or globe without requiring special screws or other retainers such as are commonly employed for this purpose. Application and removal of the shade or globe are facilitated as a simple manipulation will enable the shade or globe to be applied or removed. The ring 12, its fingers 15 and the spring 16 are all contained within the recess 14.

There is frequent need for a supplemental socket to receive the plug of appliances, such as electric fans, curling irons, water heaters, etc. in connection with bath room fixtures and it has been a common practice to use duplex sockets and special adapters to enable the current to be taken off for such purposes.

I have provided an attachment in connection with the present fixture by which current may be taken off for any desired use through the plugs of the appliances such as set forth, and for other purposes. To that end the canopy 1 is provided with slots 17 extending therethrough to enable contacts of the plug to be engaged with a socket having contacts 18 arranged in slots 19 corresponding to slots 17 and provided in a body 20 of insulating material which is secured to the canopy 1 by a small bolt 21. A suitable insulating fiber covering 22 may be provided for said attachment.

The fixture is provided at its back with an adjustable attaching plate 23 held by screws 24 by which the fixture may be secured to the wall.

A pull chain 25 operates the switch in the lamp socket and extends through a hole in the canopy 1.

It is not essential that the lamp socket be

provided with snap switch, a pull chain, or a key. The socket may be either a "key-socket" or a "keyless-socket"; the current may be controlled at the fixture or by a switch at a point removed therefrom.

The supplemental or plug-socket comprising the slots 17, 19, contacts 18, and body may be omitted, if desired.

What I claim is:

1. In a lighting fixture the combination with a canopy provided with a flange, of a sectional lamp socket, a clamping ring located between and secured by the sections of the lamp socket said ring being located on one side of the flange, and a combined shade or globe holder and clamping ring located on the outer side of the flange and connected to the inner clamping ring aforesaid, said last named ring having means for engaging the outside of the neck of a shade or globe. 75

2. In a lighting fixture the combination with a canopy, of a shade or globe holding ring attached thereto which is provided with unconfined freely projecting snap fingers, adapted to snap over and engage the neck of the shade or globe for the purpose of holding said shade, and a coil spring connecting certain ones of said fingers, said coil spring being arranged to engage the neck of the shade or globe to assist in holding the latter in position, said fingers and coil spring constituting an automatic snap fastening for connecting the shade or globe to the canopy. 90

3. In a lighting fixture, a canopy having a recess in its outer face, and provided with an internal flange, a shade or globe holder seated in said recess and against said flange, a lamp socket located within the fixture body beyond the flange and also received within the recess, and means detachably connecting the shade or globe holder to the lamp socket whereby both are held in position on the canopy with the flange interposed between them. 100

4. A lamp shade or globe holding ring having means whereby it may be attached to a canopy and provided with unconfined outstanding snap fingers adapted to engage the neck of a shade or globe, and a coil spring connecting certain ones of said fingers, said coil spring being arranged to directly engage the neck of the shade or globe to assist in holding the latter in position, said fingers and coil spring constituting an automatic snap fastening for connecting the shade or globe to the canopy. 115

5. A shade or globe holder comprising a flat ring having means whereby it may be secured to a canopy, and provided with snap fingers outstanding angularly in relation to the flat face of said ring adapted to engage the neck of a shade or globe, and a coil spring connecting certain ones of said fingers, said spring being arranged to directly 125

engage the neck of a shade or globe to assist the fingers in holding said shade or globe.

6. A shade or globe holder comprising a flat ring having means whereby it may be secured to a canopy, and provided with outstanding snap fingers springing from its inner margin outstanding angularly in relation to the flat face of said ring adapted to engage the neck of a shade or globe, the

ring being provided with means adapting it 10 for being secured in position for use, and a coil spring connecting certain ones of said outstanding fingers, said coil spring being arranged to lie crosswise of, and to directly engage, the neck of a shade or globe to assist 15 the fingers in holding said shade or globe.

In testimony whereof I affix my signature.
ROY W. SCHWEIKER.
